UNITED STATES PATENT OFFICE.

WILLIAM F. KUNKEL, OF MILWAUKEE, WISCONSIN.

SPRING BED-BOTTOM.

1,150,867.

Specification of Letters Patent. Patented Aug. 24, 1915.

Application filed February 8, 1912. Serial No. 676,265.

To all whom it may concern:

Be it known that I, WILLIAM F. KUNKEL, a citizen of the United States, residing at Milwaukee, county of Milwaukee, and State 5 of Wisconsin, have invented new and useful Improvements in Spring Bed-Bottoms, of which the following is a specification.

My invention relates to improvements in spring bed bottoms, with particular reference to that class of such devices in which the margins of the spring are turned upwardly for the purpose of retaining a mattress in position.

The object of my invention is to simplify 15 the construction of bed bottoms of the described class, whereby bed bottoms having up-turned woven wire springs may be formed without increasing the number of parts and with very little increase in the expense of construction over what is required 20 for bed bottoms having ordinary flat springs.

In the drawing the figure illustrates in perspective, one end portion of a bed bottom embodying my invention.

My improved bed bottom is formed with a frame composed of side bars A, A, and end bars of angle iron having a down-turned flange B and a horizontal flange C. The 30 horizontal flange is provided at each end with integral upwardly projecting lips or members D. These end bars may be formed of any ordinary piece of angle iron of the required length by cutting out an end section from each end of the flanges B and bending the ends of the other flange upwardly to form the members D. A woven wire spring E is adjusted over the upper surface of the flange C at each end of the 35 bed frame, and its side margins are turned upwardly and lapped upon the inner surface of the member D. The spring is then secured to the flange C and members D by a clamping member F, having up-turned integral end portions G. This clamping member is adapted to snugly fit between the up-turned end portions D and may be secured by bolts or rivets to said members D and to the flange C, the ends of the woven wire 45 spring being securely clamped between the clamping member and the members C and D.

It will of course be understood that the respective ends of the bottom frame are formed alike, each comprising but two pieces of material, one of which is shaped 55 to form the members B, C and D, and the other of which is shaped to form the members F and G. I am therefore able to construct bed bottoms of this type with the same facility that flat bed bottoms have 60 heretofore been constructed and substantially the only difference in expense consists in the additional material required for the up-turned portions. The cost of constructing and assembling is not materially increased. 65 It will also be observed that by forming the up-turned members D and G integrally with the members C and F, a structure of great strength and rigidity is provided. This is important for the reason that 70 the strains exerted by the woven wire are heavy, such wire being secured in position under high tension.

I claim:

1. A metallic frame for a spring bed bottom, having an angle iron end member provided with a horizontal flange upturned at each end, in combination with a woven wire spring having its ends lapped upon said horizontal flange and upon the upturned end 80 portions, a retaining member having a horizontal portion and up-turned end portions fitting between the upturned end portions of the angle iron flange and connected therewith in clamping relation to the ends of the 85 woven wire spring.

2. A metallic frame for a spring bed bottom, having an angle iron end member rigidly connected with the side bars and provided with a horizontal flange having integral upturned end portions, in combination 90 with a woven wire spring having its end portion lapped upon said horizontal flanges and upon the inner faces of the up-turned end portions, and rigidly secured 95 thereto.

In testimony whereof I affix my signature in the presence of two witnesses.

WILLIAM F. KUNKEL.
